UNITED STATES PATENT OFFICE.

LEONARD STUDY, OF PLUM HOLLOW, IOWA.

CLOTHES-POUNDER.

SPECIFICATION forming part of Letters Patent No. 248,232, dated October 11, 1881.

Application filed February 23, 1881. (Model.)

To all whom it may concern:

Be it known that I, LEONARD STUDY, of Plum Hollow, in the State of Iowa, have invented certain new and useful Improvements 5 in Clothes-Pounders; and I do hereby declare that the following is a full, clear, and exact description thereof, reference being had to the accompanying drawings, and to the letters of reference marked thereon, making a part of 10 this specification.

The nature of this invention relates to clothes-pounders; and it consists in the features of construction and combination herein-after described, and specifically designated in 15 the claim.

In connection with my invention I have shown and described means especially adapted for operating the same.

In the drawings, Figure 1 is a sectional view 20 of a portion of a wash-tub with my improved clothes-pounder and auxiliaries. Fig. 2 is a plan view of the under side of the pounder.

The letter A indicates a cone-shaped shell or casing, which is provided with a central tubular socket, a, connected with the cone-shaped 25 casing by a series of vertical partitions, B B. A disk-shaped valve, C, is fitted loosely upon this socket above the casing A of the pounder, and is arranged to have a limited vertical 30 play between the latter and a nut or sleeve, D, which is fitted upon the said tubular socket.

D' indicates the vertical stem of a handle, inserted into the tubular socket a, the handle E upon said stem being preferably a cross-bar 35 adapted to be grasped by the hand of the operator.

F indicates a vertical rod, having at its lower end a clip, G, which is secured by a set-screw, G', to the edge of the wash-tub. The

upper end of this rod is bent so as to extend 40 over the center, or nearly over the center, of the tub, and a spiral spring, H, is arranged to connect the upper end of this rod with the handle of the pounder. As a convenient means for effecting this connection, the rod is formed 45 with a hook at its upper end, which engages an eye of the spring, and an eye or ring, with which a hook at the lower end of the spring engages, is connected with the handle. It is obvious, however, that other means than those 50 shown may be employed for making the connection between said parts.

When the pounder is forced down through the water the valve will rise, and thus allow 55 air to pass out through the top of the pounder, whereby all splashing will be avoided. When, however, the pounder is raised the valve will be seated, by reason of atmospheric pressure 60 upon it, and hence the clothes will be raised with the pounder by its suction. In raising 65 the pounder the retractile power of the coiled spring will be found to materially assist the operator, and thereby render the operation much easier than if no spring were employed.

What I claim, and desire to secure by Letters Patent, is—

The combination, in a clothes-pounder, of the cone-shaped casing A, having an open top and bottom, the partitions B, sleeve D and its nut, the valve C, and handle D', all arranged to operate substantially in the manner specified. 70

In testimony that I claim the foregoing I have hereunto set my hand this 18th day of February, 1881.

LEONARD STUDY.
